DOOR LOCK

Rollo Marple, Jackson, Mich., assignor to Hancock Industries, Inc., a corporation of Michigan

Application June 23, 1955, Serial No. 517,419

18 Claims. (Cl. 292—279)

This invention relates to door locks, and more particularly to latching mechanisms adapted for use with doors on vehicles and other locations in which the latch is subjected to jarring and vibration. This application is related to applicant's prior Patent No. 2,803,955 issued August 27, 1957, the latching mechanism in this application being an improved version of that disclosed in the patent.

It is an object of the present invention to provide a novel and improved latching mechanism which incorporates "take-up" action for preventing looseness in the latch due to jarring and vibration, and which is nevertheless extremely easy to unlatch with a minimum of manual effort.

It is another object to provide a latching mechanism of the above nature, in which the take-up action is continuous throughout its range, and wherein the take-up and dogging means are completely retracted from engagement with the bolt during opening movement of the door, thereby eliminating all resistance of the latching parts to opening of the door, and providing a freely movable bolt.

Other objects, features, and advantages of the present invention will become apparent from the subsequent description, taken in conjunction with the accompanying drawings.

In the drawings:

Figure 1 is an end elevational view of a bolt assembly for a door latch constructed in accordance with the principles of the invention, parts being broken away for clarity, showing the outside rollback and dogging mechanism in latching position;

Figure 2 is a side elevational view of the structure of Figure 1, showing the inside rollback and locking slide;

Figure 3 is a fragmentary cross-sectional view taken along the line 3—3 of Figure 1 and showing the cooperation between the roller cam and the roller retracting member;

Figure 4 is a view similar to Figure 1 showing a portion of the mechanism with the outside rollback in its unlatching position;

Figure 5 is an end elevational view of a modified form of the invention in which a toggle linkage is used to positively retract the reaction member, the parts being shown in their latching position, parts being broken away for clarity;

Figure 6 is a fragmentary view in cross-section taken along the line 6—6 of Figure 5 and showing the roller and its cooperating parts;

Figure 7 is a view similar to Figure 5 showing the parts in their unlatching position;

Figure 8 is a rear elevational view of still another embodiment of the invention, similar in principle to that of Figures 5—7 but in which the toggle linkage is connected to the other end of the reaction member, parts being broken away for clarity; and

Figure 9 is a view similar to Figure 8 showing the mechanism in unlatching position.

As shown in the illustrated embodiments, the invention

2

comprises a mounting plate having a conventional multi-toothed rotary bolt and an abutment member for cooperation with a keeper of the type shown for example in Marple Patent No. 2,195,179 issued March 26, 1940.

5 The combined dogging and take-up means comprises a roller movable into and out of engagement with the dogging teeth on the rotary bolt. A reaction member is provided for the dogging means, this taking the form for example of a track inclined with respect to the dogging bolt teeth in such a manner that the roller, when urged along the track in one direction, will urge the bolt in a latching direction to provide the take-up motion. This basic dogging and take-up construction is disclosed and claimed in copending application Serial No. 218,447, filed March 30, 1951, by the present applicant, now Patent No. 2,712,957, granted July 12, 1955. It will be understood that other forms of take-up or dogging action could be used within the principle of the invention.

During latching movement of the bolt assembly, the 20 roller track is held in its operative position and as the bolt engages the striking surface of the keeper and is rotated, one of the dogging teeth passes under the roller which is free to retract, being spring-urged into position behind the dogging tooth to latch the bolt. The forces between the latched bolt, the roller and the track are such that the roller cannot be forced from its latching position by the bolt, but provides a take-up action causing further latching rotation of the bolt as the door undergoes jarring or vibration. When it is desired to unlatch the bolt, the 25 holding means for the track is released, permitting the track to be retracted from its operative position as the door is opened. This release of the track holding means may be supplemented by means for positively retracting the track from its operative position, as shown in the 30 embodiments of Figures 5—7 and 8 and 9. Means are also provided for positively withdrawing the roller from engagement with the bolt after initial release of the track. The roller, which would otherwise be moved against its spring pressure by the bolt as the latter rotates in an unlatching direction, is thus withdrawn from all 35 contact with the rotating bolt. Opening movement of the door therefore does not involve any action against spring pressure, and the movement may be easily effected with an absolute minimum of resistance. The latching parts may then be returned to their latching position.

40 Referring to the embodiment of Figures 1—4, the bolt assembly comprises a mounting plate 11 having a base 12 and a flange 13. A multi-toothed rotary bolt 14 is supported by mounting plate 11, this bolt being provided with a plurality of dogging teeth 15. A deck or cover plate shown at 16 in dotted lines in Figure 1 is secured by tabs 17 in spaced parallel relation with base 12. Guided between base 12 and cover plate 16 is a roller 18 shown in Figures 1 and 2, which is movable between 45 a latching position in engagement with dogging teeth 15 and a retracted or unlatching position as shown in Figure 4. A spring 19 is fixed at one end 21 between cover plate 16 and base 12, the other end 22 of the spring being engageable with roller 18. Spring 19 urges roller 18 to the right in Figures 1 and 4 to provide the camming or take-up action by engagement of the roller with dogging teeth 15.

45 A reaction member is provided in the form of a track 23 having a surface 24 along which roller 18 rides as urged by spring 19. Track 23 is disposed above bolt 14 and is pivotally supported by a pin 25 secured between cover plate 16 and base 12 of the mounting plate adjacent flange 13. Track 23 is movable between an operative position as shown in Figure 1 and a retracted position shown in Figure 4. When in its operative position, surface 24 of track 23 is so inclined relative to the dogging surfaces of teeth 15 that as roller 18 moves to the right

along surface 24, bolt 14 will be rotated counterclockwise in Figure 1. Since a latching tooth on bolt 14 engages a keeper 26 as shown partially in dot-dash lines in Figure 1, this take-up action will cause the bolt assembly and door to be moved to the right, improving the firmness of closure. This take-up action is described in detail and claimed in aforementioned Patent No. 2,712,957.

Means are provided for releasably holding track 23 in its operative position. In the embodiment of Figures 1-4, this means comprises a holding member 27 pivoted at 28 on base 12 and having a toe 29 engageable with a shoulder 31 at the outer end of track 23. When toe 29 is on shoulder 31, track 23 will be held securely in its operative position, the force transmitted from shoulder 31 to toe 29 passing through pin 28.

Holding member 27 is swingable from its holding position as shown in Figure 1 to its releasing position shown in Figure 4 by means of an outside rollback 32 pivoted at 33 to the upper portion of base 12. In particular, a pin-and-slot connection is provided between members 27 and 32, this connection taking the form of a pin 34 on the upper end of member 27 extending through a slot 35 in rollback 32. A spring partially shown at 36 is provided between mounting plate 11 and a shoulder 37 on rollback 32, urging this member in a clockwise direction as seen in Figures 1 and 4, and thus urging toe 29 into engagement with shoulder 31. The outer surface of shoulder 37 is adapted to be engaged by an outside door handle (not shown) to move rollback 32 toward its unlatching position. A sloping surface 38 is provided at the end of track 23 so that toe 29 may be guided when track 23 is away from its operative position.

Means are also provided for positively retracting roller 18 when the bolt is unlatched. This means comprises a roller retracting lever 39 pivoted at 41 between base 12 and cover plate 16. Lever 39 has an arm 42 extending downwardly from pivot 41 and engageable with a reduced shoulder portion 43 of roller 18, as best seen in Figure 3. The engagement between arm 42 and shoulder 43 is such that when lever 39 swings clockwise, roller 18 will be moved to the left in Figure 1 against the action of spring 19. The surface 44 of arm 42 which engages shoulder 43 is so inclined as to impart an upward component of movement to roller 18 during its retracting movement, so that it will be lifted clear of dogging teeth 15 as shown in Figure 4.

In the illustrated embodiment, a connection is provided between lever 39 and rollback 32 in order that the lever and the track holding means may be actuated by a single operator. This connection comprises an arm 45 on the lever provided with a shoulder 46 at its outer end. Rollback 32 has a finger 47 engageable with the underside of shoulder 46 when the rollback is moved counterclockwise in Figure 1. It will be noted that when in its normal position, shown in Figure 1, finger 47 is spaced from shoulder 46 a sufficient distance to permit toe 29 of track holding member 27 to be disengaged from shoulder 31 of track 23, before lever 39 is swung clockwise during the unlatching operation. As a result of this action, track 23 is free to be retracted under the influence of roller 18 when the latter is moved away from bolt 14.

Means may be provided for preventing movement of roller 18 toward pivot 25 of track 23, during initial rotation of bolt 14 in an unlatching direction, and guiding it toward the other end of the track. It will be appreciated that if bolt 14 is rotated in an unlatching direction (clockwise in Figure 1) with holding member 27 free from track 23 but with lever 39 still in its inoperative position, roller 18 could be moved by the rotating bolt toward pivot 25 of track 23, and could possibly become jammed in the bolt teeth or otherwise increase the resistance against which lever 39 must act. The guide means in the present embodiment comprises an edge 48 lanced or otherwise formed from base 12 of the mount-

ing plate and aligned with roller 18. Edge 48 is inclined upwardly and to the left in Figure 1, and movement of roller 18 away from bolt teeth 15 will therefore always be in a direction toward the outer end of track 23.

The bolt assembly is also provided with an inside rollback 49 pivoted at 50 on flange 13 of mounting plate 11. Rollback 49 is operatively connected with roller 18 by a lever 51 carried by pivot 41 on base 12. Lever 51 is provided with an arm 52 extending toward flange 13 and engageable by an arm 53 of rollback 49, when the latter is swung counterclockwise in Figure 2. The opposite end of lever 51 is provided with a shoulder 54 engageable with a finger 55 on outside rollback 32. Finger 55 is spaced above finger 47 so that both shoulders 46 and 54 of levers 39 and 51 respectively are disposed between these fingers. In the normal position shown in Figure 1, shoulder 54 is adjacent finger 55, so that when lever 51 is swung clockwise in this figure by unlatching movement of the inside rollback, outside rollback 32 will rotate in its counterclockwise or unlatching direction. Toe 29 will thus be retracted from shoulder 31 of track 23, and finger 47 of the outside rollback will engage shoulder 46. Roller 18 and track 23 will therefore be retracted in the same manner as occurs when outside rollback 32 is actuated directly by the outside door handle. It will be noted that spring 36, which urges outside rollback 32 clockwise in Figure 1, will maintain both lever 51 and inside rollback 49 in their normal positions.

Means are also provided, in this embodiment of the invention, for locking the outside rollback against detaching movement. This means comprises a locking slide 56 mounted on flange 13 and movable between a lower unlocking position shown in Figure 2 and an upper locking position. An overcenter spring 57 is provided for holding slide 56 in either of its positions. The upper end of slide 56 is provided with a pair of spaced fingers 58 and 59. A slot 60 is provided in flange 13, and one end 61 of a locking lever 62 is disposed within this slot and between fingers 58 and 59. This lever is pivoted on base 12 of the mounting plate by means of pivot pin 41, the lever being disposed between lever 51 and the base. The opposite end of locking lever 62 is provided with an offset blocking portion 63, this portion being in the plane of movement of lever 27. When blocking lever 62 is rotated counterclockwise from its position in Figure 1, portion 63 thereof will be aligned with edge 64 of lever 27, thus preventing substantial clockwise movement of this lever. Since lever 27 is connected by pin 34 and slot 35 with outside rollback 32, unlatching movement of roller 18 and track 23 by either rollback will be prevented.

Locking slide 56 may be actuated between its positions by reverse movement of inside rollback 49 or by a key station shaft 65. In particular, the upper end of slide 56 is provided with a shoulder 66 against which the upper edge 67 of inside rollback 49 will bear when this rollback is swung clockwise from its neutral position shown in Figure 2. The lower end of slide 56 is provided with a projection 68 engageable by a forked cam 69 mounted on key station shaft 65, the latter being rotatably supported by flange 13 of the mounting plate. Cam 69 is rotatable from its neutral position shown in Figure 2 in a counterclockwise direction, the lower end of the cam engaging projection 68 to move the locking slide to its blocking position. When rotated clockwise from its neutral position, cam 69 will engage projection 68 to move locking slide 56 to its unlocking position.

Kick-off means are also provided for moving locking slide 56 to its unlocking position when the inside handle is operated in an unlatching direction, or when the door is slammed. As shown in the illustrated embodiment, kick-off action by the inside handle is accomplished by the disposition of locking lever toe 61 adjacent end 53 of inside rollback 49 when the locking lever is in its

locking position. As will be seen in Figure 2, counter-clockwise or unlatching movement of inside rollback 49 will cause engagement of end 53 of the rollback simultaneously with toe 61 and end 52 of lever 51. Locking lever 62 will thus be moved to its unlocking position, enabling the unlatching action to take place.

The kick-off means for moving locking slide 56 to its unlocking position when the door is slammed comprises an extension 71 on one side of locking slide 56 in parallel relation with base 12. Extension 71 extends downwardly and to the left as shown in Figure 1, and when locking slide 56 is in its upper or locking position, this extension is in the path of rotation of dogging teeth 15 of bolt 14. When bolt 14 is rotated counterclockwise in Figure 1 by virtue of slamming of the door, the adjacent dogging tooth 15 will engage extension 71, camming locking slide 56 downwardly into unlocking position.

In operation of the embodiment of Figures 1-4, assume the parts are initially in the position shown in Figure 1, with the door in its latching position and locking lever 62 in its unlocking position. Under these conditions, roller 18 will be disposed between a dogging tooth 15 of bolt 14 and the inclined surface of track 23. The take-up action previously described will take place between roller 18 and bolt 14 under the influence of spring 19. If it is desired to unlatch the door from the outside, the operator causes the outside door handle (not shown) to engage shoulder 37 of outside rollback 32, the outside rollback being rotated counterclockwise. This will cause clockwise rotation of lever 27 through the medium of pin 34 and slot 35. It will be noted that the position of the pin and slot with respect to the axes of pivots 23 and 33 is such as to obtain optimum movement of lever 27. Toe 29 will be first withdrawn from shoulder 31 of track 23, freeing the track for clockwise movement about pivot 25. If the door were pulled open at this point, mounting plate 11 would be withdrawn to the left in Figure 1, rotating bolt 14 clockwise. The dogging tooth 15 adjacent roller 18 would force the roller into retracted position as guided by edge 48 against the action of spring 19. Resistance to this movement would also be presented by track 23, even though the latter is no longer positively held in position. The reason for this resistance of track 23 to retraction movement of roller 18 is that toe 29 of holding member 27 would rest against edge 38 of track 23, being pressed against this edge by the action of spring 36. Some frictional drag would thus be created, which together with the action of spring 19 would offer a variable amount of resistance to unlatching of the door.

In normal operation however, the counterclockwise or unlatching movement of outside rollback 32 will be continued until the position of Figure 4 is reached, locking lever 62 being omitted from this figure for purposes of clarity. When passing to this position, finger 47 of outside rollback 32 will engage shoulder 46 of roller retracting lever 39. Lever 39 will be swung clockwise, causing arm 42 thereof to engage reduced portion 43 of roller 18. The roller will thus be drawn upwardly and to the left until it is out of the path of bolt dogging teeth 15. During this movement track 23 will be urged clockwise by roller 18, the latter being held against track 23 by spring 19. The limiting position of rollback 32 will be reached when the space between its fingers 47 and 55 is occupied by shoulders 46 and 54, as shown in Figure 4.

With the parts held in the position of Figure 4 by the outside door handle, bolt 14 will be free to rotate, having no resistance other than the friction of rotation on its own shaft. The door may thus be opened with an absolute minimum of resistance. Upon release of the outside handle, spring 36 will urge rollback 32 clockwise into its original position shown in Figure 1. The camming action of toe 29 on track edge 38 will move track 23 back to its normal position shown in Figure 1. Roller 18

will be moved back by track 23 to its normal position in engagement with dogging teeth 15. Toe 29 will engage shoulder 31 to lock track 23 in place, and the parts will be ready for a closing operation.

When closing the door, bolt 14 will be rotated clockwise by engagement with keeper 26. The dogging tooth 15 adjacent roller 18 will cause the roller to move upwardly and to the left against the urging of spring 19. Roller 18 will drop into position behind dogging tooth 15, and the dogging and take-up action described above will take place. It should be noted that both in the latching and unlatching operations, a minimum of resistance is introduced by the retracting or unlatching mechanism. In particular, it should be observed that during unlatching of the door, it is not necessary to overcome the wedging or camming forces which exist between roller 18, track 23 and the bolt, since track 23 is initially released for retraction movement.

If the door is closed and it is desired to open the door from the inside, inside rollback 49 is rotated counterclockwise in Figure 2. This movement will cause lever 51 to rotate clockwise in Figure 1, shoulder 54 of this lever engaging finger 55 of outside rollback 32. The outside rollback will thus be rotated counterclockwise into the position of Figure 4, and the unlatching action will take place in the same manner as if the outside rollback were actuated by the outside door handle.

When it is desired to lock the latching mechanism, locking slide 56 is moved upwardly either by clockwise rotation of inside rollback 49 in Figure 2 or by counterclockwise rotation of key station cam 69. In either event, locking lever 62 will be rotated counterclockwise in Figure 1, positioning blocking toe 63 in obstructing relation with edge 64 of lever 27. Unlatching movement of outside rollback 32 will thus be prevented. If inside rollback 48 is then moved counterclockwise from its neutral position in Figure 2, toe 61 of lever 62 will be engaged to unlock rollback 32, allowing unlatching action to take place. If the door is slammed, bolt dogging teeth 15 will engage extension 71 on slide 56, moving the locking slide and locking lever to unlocking position.

Figures 5, 6 and 7 illustrate another embodiment of the invention which is similar in principle to the first embodiment but wherein a toggle linkage is provided for holding the track in its operative position. A mounting plate 72 is provided having a base 73 and a flange 74 at right angles. Pivotedly supported by mounting plate 72 is a bolt 75 having a plurality of dogging teeth 76. A roller 77 is disposed adjacent dogging teeth 76 and is urged to the right in Figures 5 and 7 by a spring 78. A reaction member or track 79 is pivotally mounted at 81 adjacent the outer edge of base 73. This track extends toward flange 74 and has an edge 82 inclined with respect to the dogging teeth with which roller 77 is engageable, in such manner as to produce the latching and take-up action described with respect to the previous embodiment.

Track 79 is movable between a normal or operative position shown in Figure 5 and a retracted position shown in Figure 7. The means for holding track 79 in its normal or operative position comprises a toggle linkage in the form of an outside rollback 83 and a connecting link 84. Rollback 83 is pivoted at 85 to the upper portion of base 73 and is provided with a shoulder 86 for engagement by a portion of an outside door handle (not shown). Link 84 is pivoted at 87 to one end of rollback 83 and is pivoted at 88 to an intermediate portion of track 79. The relative positions of pivots 85, 87 and 88 are such that pivot 87 is movable to either side of a line 89 connecting the axes of pivots 85 and 88. In particular, a stop 91 is provided on base 73 which cooperates with one edge 92 of an arm 93 on link 84. The position of stop 91 is such that it is engaged by arm 93 when the axis of pivot 87 is slightly to the left of line 89, as shown in Figure 5. A spring 94 urges rollback 83 in a clockwise direction so that arm 93 is urged into engagement with

stop 91. When in this position, it will be seen that an upward force exerted on track 79 by roller 77 will be resisted by the toggle linkage, since pivot 87 is to the left of line 89. A positive holding means is thus provided for track 79 which can only be released by moving pivot 87 to the right of line 89 in Figure 5.

The means for releasing the toggle linkage from its holding position with respect to track 79 comprises outside rollback 83 and an inside rollback 95, a portion of which is shown in Figure 5. Rollback 95 is pivoted in the usual manner on flange 74 of the mounting plate and is engageable with an arm 96 extending from connecting link 84. As shown in Figure 5, downward movement of rollback 95 will cause clockwise rotation of link 84 about pivot 88, in the same manner that outside rollback 83 would cause such rotation. Pivot 87 will thus pass to the right of line 89 releasing track 79 for movement. It will be noted that spring 94, which urges outside rollback 83 into its normal or inoperative position also serves, through the medium of link 84, to urge inside rollback 95 to its normal position.

As in the previous embodiment, means are provided for positively retracting roller 77 in addition to the release of track 79, so that bolt 75 will be freely rotatable when the door is being opened. As shown, arm 93 is provided with an edge 97 facing a pin 98 on roller 77. The relative disposition of edge 97 and roller pin 98 is shown in Figure 6, wherein it will be seen that edge 97 is in alignment with the pin but in spaced relation therewith when the toggle linkage is in its holding position shown in Figure 5. When link 84 is rotated clockwise about pivot 88 during releasing movement of the toggle linkage, edge 97 will approach pin 98. The spacing between these elements may be such that engagement of pin 98 by edge 97 will not occur until pivot 87 of the toggle linkage has passed line 89, releasing track 79. Further movement will bring the parts into the position shown in Figure 7, wherein track 79 and roller 77 are both in retracted position. It should be noted that in this embodiment, unlike the embodiment of Figures 1-4, track 79 is positively retracted through the toggle linkage, which serves to draw the track upwardly about pivot 81. The degree of movement which pivot 87 must undergo before it passes line 89 is preferably small enough to reduce to a minimum the amount of effort required in unlatching movement.

Locking means may also be provided in this embodiment for preventing unlatching movement by the inside or outside rollbacks. As illustrated, a locking lever 99 is provided, this lever being pivoted on the pivot 101 which supports bolt 75. An overcenter spring 102 may be provided between lever 99 and flange 74 for holding the locking lever in either the lower or unlocking position shown in Figure 5 or an upper or locking position. A shoulder 103 is provided at the upper portion of lever 99, this shoulder being engageable with a locking arm 104 extending from link 84. When lever 99 is rotated clockwise in Figure 5, shoulder 103 will engage the projecting end of arm 104, preventing clockwise or unlatching movement of link 84 about pin 88. Both inside and outside rollbacks will thus be prevented from unlatching the bolt assembly.

Kick-off means are also provided in this embodiment for moving locking lever 99 into its unlocking position when the door is slammed. This means comprises a kick-off edge 105 on locking lever 99 in alignment with pin 98 of roller 77, as seen in Figure 6. When the door is slammed, roller 77 will be moved to the left in Figures 5 and 6 due to bolt rotation. The spacing between pin 98 and edge 105 is such that this movement of roller 77 will cause pin 98 to engage the kick-off edge, moving lever 99 into its unlocking position.

Key-actuated means may also be provided for moving locking lever 99 between its positions. As shown, a key-actuated shaft 106 supported by a flange 107 on base

73 has a pin 108 projecting into a slotted portion 109 on lever 99. Shaft 106 may be rotated to engage the ends of slot 109 and thus move lever 99 to either its locking or its unlocking position.

- 5 In operation of the embodiment of Figures 5 and 7, assume an initial condition in which the bolt assembly is as shown in Figure 5, and the door is closed. If it is desired to open the door, leave the car and close and lock the door, inside rollback 95 will be moved downwardly 10 in Figure 5. This will cause rotation of link 84 about pivot 88. Initially, this movement will cause very slight compression of the toggle linkage until pivot 87 passes line 89. Further rotational movement will cause the toggle linkage to move into the position of Figure 7. This 15 movement will cause retraction of track 79 and will also cause retraction of roller 77, pin 98 of the latter being engaged by arm 93. When the position of Figure 7 is reached, bolt 75 will be permitted free rotation so that the door may be opened with ease.
- 20 The release of inside rollback 95 will cause the parts to return to the position shown in Figure 5. When the door is slammed, dogging teeth 76 will rotate counterclockwise in Figure 5, retracting roller 77 against the urging of spring 78, until the roller falls behind the adjacent dogging tooth. During this movement track 79 25 will remain stationary, being held by the toggle linkage. Spring 78 will urge roller 77 to the right, causing latching and take-up action to take place as described above. Key shaft 106 may then be rotated to swing locking lever 30 99 clockwise in Figure 5, engaging locking arm 104 to prevent unlatching movement.

Figures 8 and 9 illustrate still another embodiment of the invention which is generally similar to that of Figures 5-7 but in which the track or reaction member is pivoted at the opposite end. As shown, the bolt assembly comprises a mounting plate generally indicated at 111 having a base 112 and a flange 113. A bolt 114 is pivotally supported by mounting plate 111 and roller 115 serves as the dogging and take-up means for this bolt, as in the previous embodiments. A track 116 is provided for roller 115, this track having an edge which cooperates with the roller to produce the latching and take-up functions of the device. In this modification, track 115 is pivoted at 40 117 adjacent flange 113 and extends toward the outer edge of base 112. A connecting link 118 is pivoted at 119 to the outer end of the track 116 and is pivoted at its other end to an outside rollback 121 by means of a pivot 122. Outside rollback 121 is pivoted at 123 to the upper portion of base 112, in such manner that pivots 119, 122 and 123 form part of a toggle linkage for holding track 116 in position. In particular, the axis of intermediate pivot 122 is movable slightly to the left of a line 124 connecting the axes of pivots 119 and 123. A stop 125 is provided on base 112 for limiting the leftward movement of connecting link 118, thus providing a predetermined holding position for the toggle linkage. A spring 126 is connected between outside rollback 121 and base 112 urging the rollback in a counterclockwise direction, and thus urging the toggle linkage into its holding position against stop 125. An extension 127 on connecting link 118 serves to limit movement of the toggle linkage in its releasing direction. As shown in Figure 9, this extension is engageable with a flange 128 on the outer edge of base 112 to limit movement of the toggle linkage.

The means for positively retracting roller 115 in this embodiment comprises a roller retracting lever 129 pivoted at 131 on base 112. This lever has a shoulder 132 at one end thereof disposed between a pair of fingers 133 and 134 on outside rollback 121. Lever 129 is further provided with an arm 135 extending downwardly and in spaced alignment with a pin 136 on roller 115. Arm 135 is engageable with pin 136 when lever 129 is rotated clockwise in Figure 8, to retract roller 115 in the same manner as in the previous embodiments. Preferably,

finger 133 is slightly spaced from shoulder 132 to permit the toggle linkage to release track 116 before roller 115 begins its retracting movement.

An inside rollback, shown partially at 137, is also provided in this embodiment of the invention. The inside rollback, which may be pivoted on flange 113 of the mounting plate, is movable downwardly in Figure 8 into engagement with an arm 138 on lever 129. The subsequent clockwise rotation of lever 129 will cause engagement of shoulder 132 with finger 134 on outside rollback 121. The toggle linkage will thus be broken, and track 116 as well as roller 115 retracted by inside rollback movement.

It is believed the operation of the embodiment of Figures 8 and 9 is clear from the figures and from the description of operation of the previous modifications. Starting with the condition shown in Figure 8, if it is desired to unlatch the door from the outside, outside rollback 121 is rotated counterclockwise in Figure 8 by the outside door handle (not shown). The toggle linkage comprising the outside rollback and link 113 will move from its track holding position to its track releasing position, permitting retracting movement of track 116. At the same time, lever 129 will be rotated clockwise in Figure 8, causing engagement of arm 135 with pin 136 of roller 115. The roller will thus be retracted out of engagement with bolt 114, the latter being permitted free rotation during the door opening movement, as shown in Figure 9.

While it will be apparent that the preferred embodiments of the invention disclosed are well calculated to fulfill the objects above stated, it will be appreciated that the invention is susceptible to modification, variation and change without departing from the proper scope or fair meaning of the subjoined claims.

What is claimed is:

1. In a vehicle door latching mechanism, a rotatable bolt, a dogging member movable between an unlatching position free from said bolt and a latching position in engagement with said bolt, a spring urging said dogging member into its latching position, a reaction member mounted adjacent said dogging member, said reaction member being movable between a retracted position and an operative position maintaining said dogging member in latching engagement with said bolt, holding means for said reaction member, said holding means being movable between a releasing position permitting movement of said reaction member toward its inoperative position and a holding position preventing such movement, a retracting member movable between an inoperative position and a retracting position moving the dogging member into its unlatching position, inside and outside rollbacks, and means responsive to movement of either of said rollbacks for moving said holding means into its releasing position and moving said retracting member into its reTRACTING position.

2. A bolt assembly comprising a multi-toothed rotary bolt, a roller engageable with said bolt and movable between a latching position and an unlatching position away from said bolt, a spring urging said roller into its latching position, a track adjacent said roller and engageable therewith, said track being so inclined relative to said bolt teeth as to cause said roller to rotate said bolt in a latching direction as said roller is advanced along said track by said spring, means movably supporting said track for movement between an operative position in engagement with said roller and a retracted position, means for positively holding said track in its operative position, a roller retracting member movable between an inoperative position and a roller retracting position holding said roller in its unlatching position, a rollback movable between a normal position and an unlatching position, and means responsive to movement of said rollback to its unlatching position for moving said holding means to its releasing position and moving said roller retracting member to its roller retracting position.

3. In a bolt assembly, a rotary multi-toothed bolt, a roller movable between an unlatching position away from said bolt and a latching position in engagement with the bolt teeth, a spring urging said roller into its latching position, a track pivotally mounted adjacent said roller, said track being movable between a retracted position and an operative position in engagement with said roller, the track when in its operative position providing a reactive surface for said roller enabling the latter to perform a dogging function with respect to said bolt, a holding member mounted adjacent said track, said holding member being movable between a releasing position permitting movement of said track toward its retracted position and a holding position positively holding said track in its operative position, a roller retracting lever mounted adjacent said roller, said lever being movable between an inoperative position and a roller retracting position holding said roller in its unlatching position, resilient means urging said track holding member into its holding position and said roller retracting lever into its inoperative position, an outside rollback movable between a normal position and an unlatching position, and means responsive to movement of said outside rollback to its unlatching position for moving said holding means to its releasing position and moving said roller retracting lever to its roller retracting position.

4. The combination according to claim 3, further provided with an inside rollback movable between a normal position and an unlatching position, and means responsive to movement of said inside rollback to its unlatching position for moving outside rollback to its unlatching position.

5. The combination according to claim 3, further provided with a locking member movable between an unlatching position and a locking position preventing movement of said holding member to its releasing position and said roller retracting lever to its roller retracting position.

6. The combination according to claim 3, said means responsive to movement of the outside rollback comprising a positive connection between said outside rollback and said holding member, and a lost-motion connection between said outside rollback and said roller retracting lever, said lost motion being such that upon movement of said outside rollback, said holding member will be moved to its releasing position before said roller retracting lever starts movement of said roller to its unlatching position.

7. The combination according to claim 3, further provided with a stationary guide adjacent said roller so disposed as to guide said roller away from said track pivot when the roller is moved toward its unlatching position.

8. In a bolt assembly, a mounting plate having a base and a flange, a multi-toothed rotary bolt supported by said base, a roller mounted adjacent said bolt and movable between an unlatching position away from the bolt teeth, a spring urging said roller toward its latching position, a track pivotally mounted on said base and movable between a retracted position and an operative position adjacent said roller, said track when in its operative position being so disposed relative to said bolt teeth as to present a reactive surface enabling the roller to perform a dogging function, a stationary guide adjacent said roller so disposed as to guide said roller away from said track pivot when the roller is moved in an unlatching direction, a shoulder at the outer end of said track, a holding member pivoted on said base and having a toe engageable with said shoulder, said toe being movable between a releasing position away from said shoulder and a holding position engaging said shoulder to hold said track in its operative position, a guiding edge at the outer end of said track for guiding said holding member when said track is moved away from its operative position, an outside rollback pivoted on said base, a spring urging said outside rollback into its normal position, a pin-and-slot connection between said outside rollback and said holding mem-

ber, whereby movement of said outside rollback toward its unlatching position will cause movement of said holding member toward its releasing position, a roller retracting lever pivoted on said base, said lever having an arm engageable with said roller and being movable between an inoperative position and a roller retracting position holding said roller in its unlatching position, a shoulder on said roller retracting lever, a finger on said outside rollback, said finger being in spaced relation with said shoulder when said outside rollback is in its normal position and being engageable with said shoulder to move said lever into its roller retracting position when said outside rollback is moved to its unlatching position, the spacing between said finger and said shoulder being such as to permit movement of said holding member too away from said track shoulder before engagement between the finger and lever shoulder occurs, an inside rollback pivoted on said flange and movable between a normal and an unlatching position, a connecting lever pivoted on said base and having a first arm engageable by said inside rollback when moved toward its unlatching position, a second arm on said connecting lever having a shoulder disposed adjacent the shoulder of said roller retracting lever, and a second finger on said outside rollback engageable by said connecting lever shoulder, whereby movement of said inside rollback toward its unlatching position will cause movement of said outside rollback toward its unlatching position.

9. The combination according to claim 8, further provided with a locking slide on said mounting plate flange, an overcenter spring for holding said locking slide in either a locking or an unlocking position, a locking lever pivoted on said base and movable by said slide between locking and unlocking positions, a locking arm on said locking lever having a shoulder disposable in obstructing relation with said holding member when said locking arm is in its locking position, whereby movement of said holding member from its holding position is prevented, and a portion on said locking lever disposable adjacent said inside rollback when the locking lever is in its locking position, whereby initial movement of said inside rollback toward its unlatching position will move said locking lever into its unlocking position.

10. The combination according to claim 9, said locking slide being further provided with an extension thereon, said extension being positionable in the path of said bolt teeth when the locking slide is in locking position, whereby latching rotation of said bolt teeth will cause movement of said locking slide into its unlocking position.

11. In a bolt assembly, a multi-toothed rotary bolt, a roller adjacent said bolt and movable between an unlatching position away from said bolt and a latching position in engagement with said bolt, a spring urging said roller into its latching position, a track pivoted adjacent said roller and movable between a retracted position and an operative position adjacent said roller, said track when in its operative position presenting a reactive surface to said roller enabling the roller to perform a dogging function, an outside rollback pivoted adjacent said track and movable between a normal position and an unlatching position, a spring urging said outside rollback into its normal position, a connecting link pivoted to said outside rollback and to said track, said outside rollback and connecting link forming a toggle linkage for moving said track between its operative and retracted positions, a stop limiting movement of said outside rollback by said spring past its normal position, whereby said track will be positively held in its operative position with said toggle linkage slightly past its overcenter position, an arm in spaced relation with a portion of said roller, said arm being movable between an inoperative position when said toggle linkage is in its holding position and a roller retracting position when said outside rollback is moved to its unlatching position, said arm when in its roller retracting position

holding said roller in its unlatching position, and means responsive to movement of said outside rollback to its unlatching position for moving said arm to its roller retracting position.

12. The combination according to claim 11, further provided with an inside rollback movable between a normal position and an unlatching position, and means responsive to movement of said inside rollback to its unlatching position for moving said track to its retracted position and said roller retracting arm to its roller retracting position.

13. The combination according to claim 12, said roller retracting arm being formed on said connecting link, said means responsive to inside rollback movement comprising a second arm on said connecting link engageable by said inside rollback when moved toward its unlatching position.

14. The combination according to claim 11, further provided with a locking lever movable between a retracted position and a locking position in obstructing relation with a portion of said connecting link, whereby said toggle linkage is prevented from moving from its holding position.

15. The combination according to claim 14, said locking lever being further provided with a kick-off surface positionable adjacent a portion of said roller when the locking lever is in its locking position, whereby said roller will engage said kick-off surface when moved towards its unlatching position to cause movement of said locking lever into its unlocking position.

16. The combination according to claim 11, said roller retracting arm being formed as part of a pivoted lever, said means responsive to outside rollback movement comprising a second arm on said lever having an operative connection with said outside rollback, a third arm on said lever, and an inside rollback movable between a normal position and an unlatching position, said inside rollback being engageable with said third arm when moved toward its unlatching position to move said roller retracting arm to its roller retracting position and said outside rollback to its unlatching position.

17. In a door latching mechanism, a bolt rotatable in a latching direction and an unlatching direction, first and second angularly related surfaces on said bolt, a dogging member having an operative position in opposed relation with said surfaces and a retracted position, rotation of said bolt in its latching direction urging said dogging member in a first path of movement, rotation of said bolt in its unlatching direction urging said dogging member in a second path of movement, reaction means movable between an operative position and a retracted position, a surface on said reaction means engageable with said dogging member, said last-mentioned surface being in a non-obstructing position with respect to said first path of movement but in an obstructing position with respect to said second path of movement when said reaction means is in its operative position, said last-mentioned surface further being in a non-obstructing position with respect to both paths of movement when the reaction means is in its retracted position, means separate from said dogging member for holding said reaction means in its operative position to prevent movement of the dogging member in its second path, and operating means for releasing said holding means, said operating means further including a member engageable with said dogging member for positively moving the dogging member toward its retracted position.

18. The combination according to claim 17, further provided with a spring urging said dogging member into its operative position.
